DESIGN FOR A FLASHLIGHT SWITCH

Nathaniel M. Olanoff, New York, N. Y., assignor
to Bond Electric Corporation, Jersey City, N. J.,
a corporation of Delaware

Application October 6, 1934, Serial No. 53,505

Term of patent 14 years

To all whom it may concern:

Be it known that I, Nathaniel M. Olanoff, a citizen of the United States and residing at New York, county of New York, and State of New York, have invented a new, original, and ornamental Design for a Flashlight Switch, of which the following is a specification, reference being had to the accompanying drawing, forming a part thereof.

Figure 1 is a side elevational view of a flashlight switch showing my new design;

Figure 2 is a plan view thereof; and
Figure 3 is a view in end elevation looking from below in Figure 2.

I claim:

The ornamental design for a flashlight switch substantially as shown.

This specification signed this 26th day of Sept. 1934.

NATHANIEL M. OLANOFF.
